Primary Examiner — Janice Hallmark*Assistant Examiner* — Suzanne E Tisdell(74) *Attorney, Agent, or Firm* — Seed IP Law Group LLP(57) **CLAIM**

The ornamental design for a grille accent top panel, as shown and described.

DESCRIPTION

FIG. 1 is a perspective view of a grille accent top panel showing our new design in the environment of a vehicle; FIG. 2 is a front perspective view of the grille accent top panel shown in FIG. 1;

FIG. 3 is a front view thereof;

FIG. 4 is a top view thereof;

FIG. 5 is a right side view thereof; and,

FIG. 6 is a left side view thereof.

The broken lines shown in FIG. 1 illustrate environmental subject matter that forms no part of the claimed design. The broken lines in FIGS. 2-6 illustrate portions of the grille accent top panel that form no part of the claimed design.

1 Claim, 3 Drawing Sheets(56)
